CHARGE FORMER

Theodore A. St. Clair, Pontiac, Mich., assignor to
Phillips Petroleum Company, a corporation of
Delaware

Application August 4, 1941, Serial No. 405,437

2 Claims. (Cl. 261—10)

This invention relates to a motor fuel system utilizing hydrocarbon compounds having wide boiling ranges. More particularly it relates to a method and apparatus for metering a volatile fuel.

An object of the present invention is to provide a method and apparatus for carbureting high vapor pressure fuels.

Another object of this invention is to provide such a system, operating without the use of pressure reducing regulator means, whereby the latent heat of vaporization is used for the retention of a volatile fuel in the liquid state.

A further object is to provide apparatus operating with a constant liquid level and a liquid feed of highly volatile fuel to an internal combustion engine.

Another object of the invention is to obtain a reduction of the vapor pressure by cooling the liquid fuel through means of a partial vaporization of the fuel.

Still another object is to provide means for keeping the fuel in liquid form and to prevent vaporization thereof, before the fuel enters the vaporization chamber, by reducing the temperature of the fuel to a point where the fuel is and remains in a liquid state.

Other objects and advantages will be apparent from the following detailed description taken in conjunction with the accompanying drawing, forming a part of this specification and in which:

Figure 1 is a vertical section, partly in elevation, through a preferred embodiment of this invention, and

Figure 2 is a similar view of a modified form of this invention.

Referring now more particularly to Figure 1, the numeral 10 indicates generally the upper of two main castings making up the metering apparatus. This upper casting which may be made of any preferred material, contains a float chamber 26 formed by the circular wall 11 and bottom end wall 12. The upper part of casting 10 forms an adapter and air intake pipe 13 for an air cleaner, not shown.

Flanged to casting 10 is the lower casting 14 containing a vaporization chamber 15 formed by an annular wall 16 and a bottom end wall 17. This casting also forms the main and lower part 18 of intake pipe 13 which is connected in the usual manner to the engine intake manifold. Mounted within this part 18 of the intake pipe is a Venturi tube or section 19 having a main liquid discharge jet 20 formed in conduit 21 which extends through the venturi and communicates

5 with one end of the vaporization chamber 15. A vertical passage 22 bored within wall 23 of casting 14 communicates at its upper end with conduit 21 and at its lower end with the air intake pipe 5 below the throttle valve 24 rotatably mounted therein. An idling adjustment screw 25 as commonly used on standard carburetors projects into passage 22 and provides a means for manually adjusting and controlling the flow of fluid from 10 this passage.

The float chamber 26 contains a float 27 having a stem 28 extending from the upper end and a coil spring 29 encircling this stem. Spring adjustment screw 30 is centrally bored and adapted to be slidably mounted upon stem 28 and engage spring 29. External threads on screw 30 engage threads cut into the interior of passage 31 in the upper part of casting 10. A removable closure member 32 is provided to seal the upper 20 end of passage 31 and allows access to the adjustment screw. In this way sufficient loading may be placed on the float to secure proper functioning of the apparatus during operation of the engine.

25 Conduit 33 bored within the upper part of casting 10 communicates at its lower end with the interior of float chamber 26 and at its other end with the interior of the air intake pipe 13. Vapor outlet adjustment screw 34 is mounted so as to project into this passage and provides a means for manually controlling the flow of vapor through this passage.

30 Mounted within an aperture formed in wall 12 is a tubular collar 35 which extends down through a similar aperture in wall 17. A fluid tight engagement between the collar and the walls prevents leakage from the float chamber into the vaporization chamber. Gaskets of rubber or other suitable material may be used if preferred 40 for this purpose as shown at 36. Welded to the under side of wall 17 is a valve body member 37 having a central passage 38 of varying diameters bored therein. The lower end of collar 35 seats within this passage as at 38'. A valve 39 preferably of the tire core type is mounted within this passage having a depressable head 40 extending up into a central passage 41 bored through collar 35 and aligning with passage 38. Projecting from the bottom of float 27, stem 42 extends through passage 41 in collar 35 contacting head 40 of valve 39. In this way downward movement of the float will depress head 40 opening valve 39 and upward movement of the float will cause the valve to close. Normally valve 39 is closed and is open only when head 40 is held

down, permitting fluid to flow through the interior of the valve from inlet passage 38.

A second aperture in wall 12 has a removable plug 43 mounted therein which is centrally bored to form the main metering orifice of the present device. It will be seen by reference to the drawing that fluid communication between the float chamber and the vaporization chamber occurs through this orifice.

An insulating jacket 44 of cork, or any other similar material suitable for insulating purposes, is attached to the exterior sides of casting 14 so as to surround both the vaporization chamber and the lower part of the air intake pipe.

Liquid fuel flows through line 45 which is connected in the customary manner to the lower end of passage 38. An oil pressure operated shut-off valve 46 is also connected to line 45 having an oil pressure line at 47 and the customary manual starting lever 48 adapted to be operated from the driver's compartment.

In operation the shut-off valve shown in Figure 1 is opened manually or by oil pressure and liquid fuel enters the float chamber through inlet valve 38 to a predetermined level as indicated by the reference line A—A. At first, vaporization will take place in the float chamber as well as in the vaporization chamber. Vapor formed in float chamber is then carried into the air intake pipe 13 through the vapor balance conduit 33. After the system has become cool, the temperature of the fuel being reduced to the boiling point at atmospheric pressure so that it will remain in a liquid state, vaporization within the float chamber will cease or be reduced to a small amount. Vaporization will then be practically confined to the vaporization chamber surrounding the float chamber. The partial vaporization of the liquid fuel itself effects a cooling which tends to remove heat from the inner float chamber and thereby reduces the vapor pressure of the liquid therein.

When a stream of air passes through the Venturi tube 19, the lower end 18 of the air intake pipe 13 being connected to the intake manifold of the engine, a reduced pressure exists in the discharge jet 20 and in the vaporization chamber 15. As the pressure is lowered, the liquid in chamber 15 will rise sufficiently above the level A—A to register with the conduit 21. Fuel flows through orifice 43 from the float chamber into the vaporization chamber and out through the main discharge jet into the air stream which carries it into the combustion chamber of the engine. This jet being designed sufficiently large to operate with fuel in either vapor or liquid form, will under normal conditions discharge the fuel initially in liquid form. After a short period of running, the vapor formed above the liquid in the outer vaporization chamber will cause the liquid level to depress sufficiently to permit simultaneous withdrawal of liquid and vapor through conduit 21.

which will be the equilibrium condition of normal operation. The flow through the main metering jet 43, however, will always be entirely liquid, thus providing accurate proportioning.

Figure 2 shows a modified form of the present invention in which the air intake pipe 13' containing a Venturi tube 19' and throttle valve 24' is a separate, not an integral unit of the vaporization chamber. A vapor balance line or conduit 33' is provided and connects the upper part of the float chamber 26' with the air intake pipe. The main discharge jet 20' is connected by a suitable conduit 49 to the lower part of the vaporization chamber 15'. In other respects the device shown in Figure 2 is similar in construction and operation to that shown and described for Figure 1, except that the fuel in the chamber 15' will vary from the level B—B upon starting to a level C—C after a short running period.

It will be noted that this device is somewhat similar to a standard gasoline carburetor and therefore may incorporate features such as accelerating pumps and main load jets, or other refinements as commonly used on such equipment to improve the operation, if desired. Applicant contemplates using such refinements with his present device but for the sake of brevity has not included a description or drawing thereof since they do not form an essential part of the present invention.

While the applicant has described a specific embodiment, it is to be understood that the form, herewith shown and described, is a preferred example only and that various modifications may be made therein without materially departing from the spirit of this invention as defined by the appended claims.

Having thus described my invention, I claim:

1. Charge-forming apparatus for utilizing hydrocarbon fuels, certain components of which possess a superatmospheric vapor pressure comprising in combination, a fuel reservoir having a float controlled inlet, a separate chamber substantially surrounding the side and bottom walls of the fuel reservoir in heat exchange relationship therewith, said chamber having an outlet at an intermediate point to form a closed compartment in the upper portion thereof, a metering orifice in the bottom wall of the reservoir, an air passage including a Venturi tube, a fuel discharge conduit extending from said outlet to the Venturi tube to subject the chamber to low pressure and cause vaporization of the high pressure components therein, the cooling effect thereby produced being imparted to the fuel reservoir to cool and prevent vaporization of fuel therein.

2. The apparatus of claim 1 wherein a layer of heat insulating material surrounds the chamber and air passage.

THEODORE A. ST. CLAIR.
